UNITED STATES PATENT OFFICE.

THOMAS B. HENDERSON AND DONALD P. MUSE, OF JUNCTION CITY, ARKANSAS.

MAIL CATCHER FOR AEROPLANES.

Application filed May 28, 1919. Serial No. 300,748

To all whom it may concern:

Be it known that we, THOMAS B. HENDERSON and DONALD P. MUSE, citizens of the United States, residing at Junction City, in the county of Union and State of Arkansas, have invented certain new and useful Improvements in Mail Catchers for Aeroplanes, of which the following is a specification.

This invention relates to improvements in mail catchers for aeroplanes and in general consists of certain towers having suitable guiding wires, and a delivery means connected to the mail bag. It furthermore consists of a means whereby the aeroplane is not affected by the sudden engagement with the mail bag.

With these and other objects in view, the invention consists in the construction, combination and arrangement of parts as will be hereinafter fully described, illustrated in the accompanying drawings, and pointed out in the claim hereunto appended.

Figures 1 and 2 are views showing the construction on which the tower and guide wires may be positioned, the former showing an aeroplane in position for carrying off the mail bag from one of the towers.

Fig. 3 is a top plan view of a section of the tower platforms, the guide wires and mail bag, the latter being in proper position with its equipment to engage with the cable from the aeroplane, and

Figs. 4 and 5 are detailed views of the attachment means connected with the mail bag.

Referring to the drawings like numerals designate like parts in the various drawings.

A and A¹ are suitably constructed towers preferably made of metallic frame work and provided at their upper ends with platforms F and F¹. These platforms are centrally spaced apart only by a few inches as will be noted more fully in Fig. 3. C and C¹ are guide wires fastened at their inner ends in the cleats M and M¹, which cleats are attached respectively to the inner ends of the platforms F and F¹. These guide wires C and C¹ extend forwardly from the towers A and A¹ in a V-shaped direction, their outer ends being secured to the upper ends of poles B and B¹. These poles B and B¹ are supported in their upright position by

means of guy wires D and D¹. The guy wires D², which may be of any desired number, support the towers and platforms.

Platform F¹ is provided with a latch holder N⁰. This latch holder is for holding the latch N¹⁰. The latch N¹⁰ is provided with a frame N¹¹ and a keeper N² which is hingedly connected at one end to one end of the frame N¹¹. Pin N⁶ acts as a stop pin to limit the closing movement of keeper N². N⁶ is a spring arrangement at the opposite end of the frame adapted to engage the end of the keeper when closed and prohibit the opening of the same. A chain N¹⁶ is connected between the mail bag and this end of the frame which frame is taken up by the cable. N¹² is an arm fulcrumed at 13 which may be used in connection with the latch holder N⁰. One end of this arm N¹² presses on the top of the latch to hold it against the platform F¹, while the other end of arm N¹² is pressed upwardly by the spring N¹⁴.

The cable X, after being let out from a drum on the airplane, is guided by the aviator so as to come between guide wires C and C¹. This cable is provided with the weight O at its lower end and a coil spring O¹ over said weight and a disk O² over said coil spring. The springs of the disk are used on this cable so as to lessen the impact of the latch as it falls against the disk O².

In Figure 3 we show by an arrow the direction in which the cable would be travelling before engaging with the mail bag latch. In Fig. 5 we show an arrow as designating the direction the cable would travel, showing that it will hit the short angular end N² of the keeper N¹². When it hits this portion of the keeper the keeper will close, its outer end becoming engaged with the spring N⁶. The cable will thus be engaged in position as shown in Fig. 4 and will carry off a mail bag.

As the ability of the aviators to direct their machines over a certain point increases it may be possible and practical to use only one tower, doing away with the tower designated by F. The aviator will then have the cable X guided along the guide wire C¹ and pick up the mail bag in this way. By using one tower this apparatus could be in-

stalled on a building in the down town district thus doing away with the transportation to and from suburbs of the city.

From the foregoing it is thought that the 5 construction of our invention will be clearly understood, and therefore a more extended explanation has been omitted.

What we claim as new, is,—

In a mail catcher for aeroplanes comprising a pair of spaced towers, a platform 10 on the upper face of each of said towers, the inner ends of said platforms being slightly spaced from each other, guide wires each attached at one end to the inner end 15 of one of the platforms and radiating in a

V-shape, the outer ends of said wires being supported by upright posts, a latch holder on the inner end of one of said platforms, and a latch adapted to be connected to a mail bag and having a suitable keeper 20 hingedly connected at one end so as to close when a cable suspended from an aeroplane is drawn between said keeper and said latch.

In testimony whereof we affix our signatures in the presence of two witnesses.

THOMAS B. HENDERSON.

DONALD P. MUSE.
